UNITED STATES PATENT OFFICE.

SAMUEL L. SAUNDERS, OF BOSTON, MASSACHUSETTS.

ROTARY INTERNAL-COMBUSTION ENGINE.

1,271,777.

Specification of Letters Patent.

Patented July 9, 1918.

Application filed October 9, 1916. Serial No. 124,632.

To all whom it may concern:

Be it known that I, SAMUEL L. SAUNDERS, citizen of the United States, and resident of Boston, State of Massachusetts, have invented certain new and useful Improvements in Rotary Internal-Combustion Engines, of which the following is a specification.

This invention relates to internal combustion engines and more particularly to that type of engine which employs a rotary driving member or rotor in lieu of reciprocating pistons.

One of the principal objects of the invention is to produce a rotary motor of this type which shall be entirely free from reciprocating parts so as to reduce vibration to a minimum. To this end the invention comprises essentially a rotor of the turbine type so mounted in the stationary element forming the casing as to receive from the ignition of an explosive mixture driving impulses at stated intervals during its rotation, rotary means being provided for feeding an accurately measured supply of the combustion gas for each explosion, said means being also adapted to secure compression of the gaseous mixture in the combustion chamber and in the intervals between successive ignitions.

With the construction and arrangement characterizing this invention it is unnecessary to employ external means for forcing the gaseous mixture into the casing under pressure since the feed devices themselves produce sufficient suction to draw in the carbureted air or mixture and furthermore act to compress this mixture in the combustion chamber.

The device embodying my invention embraces essentially a turbine-rotor mounted in a surrounding casing, which casing carries interiorly disposed rotary feed and compressing elements directly communicating with their respective combustion chambers which are arranged preferably inside the rotor element and adjacent thereto, so that the combustion gases impinge directly against the vanes or buckets of the rotor during their expansion outward away from the center, the feed elements acting also to prevent any back-firing into the supply pipe or chamber.

In the accompanying drawings I have illustrated in simple form the principles of construction covering this invention, but it

will be understood that the details of construction such as the shape of the buckets or vanes, the shape of the feed teeth and the proportion of parts are more or less conventionally shown to clearly illustrate the principle of the invention and may be varied to secure the highest efficiency in practice.

Figure 1 is a vertical section on the plane indicated by broken line $x-x$ of Fig. 2.

Fig. 2 is a central vertical section of the construction shown in Fig. 1.

In the practice of the invention as in the form illustrated I provide a hollow casing 1, which may be made in two approximately cylindrical sections having covering flanges 2 by which they may be tightly folded together, face to face.

The present form of device is shown as having a duplex rotor, that is, a rotor having two distinct series of buckets in offset planes and consequently two sets of explosion chambers and coördinated feed devices mounted in the casing.

In this duplex form of the invention each section or half of the casing is provided with a cylindrical head 5 which heads extend inwardly toward each other in an axial direction and form an interior casing in which are located the combustion chambers, feed members, etc.

The rotor 6 comprises a central disk-like spider 7 keyed or otherwise secured to the central shaft 4 and also a peripheral member 8 which extends in the form of a lateral annular flange in an axial direction for a suitable distance each side of the central disk or spider. At symmetrical intervals this cylindrical flange is provided with a series of buckets forming impact and expansion chambers shown at 9. Preferably each set of buckets is circumferentially staggered with reference to the set of buckets on the other side of the spider so that the explosions on one side of the middle of the rotor alternate with the explosions on the other side but this is not a necessary or indispensable arrangement.

As shown in Fig. 2 the inwardly projecting heads 5 which form a sort of interior casing within the rotor have their opposed inner faces located so as to leave a narrow annular clearance space between the disk spider of the rotor and the opposite faces of the two casing heads so as to permit the insertion of a circular internally toothed rack 10 which is fastened in any suitable

manner to the inside circular face of the rotor adjacent to its central spider, which serves a purpose presently to be described. These internal heads 5 are also provided with three partition walls 12 symmetrically arranged about the axial center to inclose the feeding and compressing members which in this case comprise intermeshing gears 13, 14 whose axial length is equal to the breadth of the chambers in which they are mounted so that they will form a close contact with the end walls of said chambers 12.

Each of the chambers 12 is provided with an inlet pipe 15 for admitting the carbureted or gaseous mixture. Both gear members have teeth of a formation best adapted to maintain a close and constant contact to prevent leakage or back-firing into the inlet or supply chamber from the explosion chamber. The wall or partition 12 is curved at opposite ends to form a close peripheral contact with half, or even more than half, of the teeth of each intermeshing gear.

The pinion 13 turns freely on a fixed stud 13^a. The pinion 14 is mounted on a shaft 14^a which projects through the inside wall of the containing chamber into the annular clearance space that is bounded by the internally toothed ring 10 and on its inner end said shaft carries a pinion 16 preferably of smaller diameter than the gear 14^a which pinion intermeshes with the teeth of the driving ring 10. It will be understood that the size of this driving pinion 16 may be varied provided, of course, the toothed ring 10 is extended far enough toward the central axis to intermesh with the pinion. By making the pinion small as compared with the gear 14^a and extending the rack bar inwardly sufficiently to engage it the speed of rotation of the feed members 13-14 may be increased to secure a greater compression of the combustible mixture.

As indicated in the drawings the rotor is assumed to travel in a contra-clock-wise direction and makes the pinion 16 and its connected gear 14 rotate in the same direction about their fixed axes while the intermeshing gear 13 rotates in a clock-wise direction. The effect of this is that the combustible mixture entering the chamber at its inner side, that is, the side toward the central shaft of the rotor, is drawn in opposite directions by the respective gear teeth and passes around the outer sides of the respective gears to the combustion chamber at 17, in which combustion chamber is mounted a suitable spark plug 18 which serves at proper intervals to ignite the mixture.

The mixture in the explosion chamber 17 is confined by the surrounding solid portion of the flange 8 of the rotor and is therefore compressed by the positive feeding action of the two gears until the passages through the bucket portion of the rotor approach the

respective combustion chambers at which instant the ignition takes place with the result that the explosive mixture impinges against the inclined vanes or buckets to produce the rotation of the rotor.

70

I have not attempted to show the ignition control since any suitable or well-known device in connection with the spark plug may be employed.

I may core out the interior of the casing 75 heads 5 between the walls 12 bounding the gear chambers and the peripheral wall and central hub to leave spaces 20 which may be employed for the circulation of air or water for cooling purposes if desired, in 80 which case suitable inlets and outlets as indicated at 21 are provided.

What I claim is:

1. A rotary internal combustion engine 85 embracing in combination a hollow casing, a rotor mounted inside said casing and having a peripheral bucket ring whose buckets are disposed to receive the impact of the explosion by which the rotor is driven, suitable combustion chambers arranged inside 90 the casing in co-operative relationship with said bucket ring, and continuously rotating gas feeding members acting by their rotation to compress and feed the combustible mixture into said combustion chambers, said 95 rotary feed members having operative connection with said rotor by which they are continuously rotated, substantially as described.

2. In an internal combustion engine the 100 combination of a rotor element provided with a series of peripheral buckets to receive the impact of the gas explosion, a casing formed to surround said rotor and also to project inside the peripheral portion of said 105 rotor, a plurality of feed devices arranged in recesses formed in the inside portion of said casing and comprising rotary feed members arranged in co-operative pairs in each 110 recess and acting to divide said recesses into inlet and outlet chambers, the latter being disposed to open into said buckets at intervals during the rotation of the buckets and forming explosion chambers, said feed members acting also to force the explosive mixture into said explosive chambers, substantially 115 as described.

3. In a rotary internal combustion engine the combination of a rotor provided with inclined buckets and secured to a central shaft, 120 a casing in which said rotor is mounted, said casing being provided with a series of pockets or recesses rotary feed and compressing devices arranged in said recesses to sub-divide them into inlet and outlet chambers, 125 said outlet chambers serving as explosion chambers and located to discharge against the buckets of the rotor as they pass in front of the outlets of said chamber, substantially 130 as described.

4. In a rotary internal combustion engine the combination of a stationary casing provided at intervals about a common center with a series of recesses, coöperating rotary members mounted in said recesses to sub-divide them into inlet and outlet chambers, a rotor comprising an annular member having buckets inclined to its radii at intervals about its periphery, said buckets being arranged to receive the explosive discharge from said outlet chambers at intervals during their rotation, said rotary members acting to feed the combustible mixture into the said outlet chambers and to compress it in the intervals between explosions, substantially as described.
5. In a rotary internal combustion engine the combination of a stationary casing provided with a series of recesses about its center, rotary devices mounted in said recesses and comprising a pair of gear-like members formed to intermesh with each other to maintain constant contact between them and having close contact with the surrounding walls of their containing recesses in order to feed the combustible mixture from one side of said recess to the other side while preventing back-firing into the inlet portion of said recess, a rotor comprising an annular member having inclined buckets arranged at intervals around its periphery to receive the discharge of the explosion produced in the outlet side of said recesses, substantially as described.
6. The combination of a rotor comprising a central spider secured to a shaft and having a peripheral annular portion formed with inclined buckets, a casing having oppositely disposed heads to project inside the annular portion of said rotor, said heads being formed with recesses arranged around the central axis, feed and compressing members mounted in said recesses to sub-divide them into inlet and outlet portions, the latter being arranged in the periphery of said heads to discharge into the buckets as they pass by in their revolution, said feed and compression members being operatively connected by suitable gearing with the rotor in order to cause their positive rotation, substantially as described.
7. A combination of a rotor comprising a central supporting spider and a peripheral annular bucket ring projecting laterally beyond said spider, a casing provided with a cylindrical head extended inside the annular peripheral member of said rotor, a series of recesses formed in said cylindrical head to receive the combustible mixture, rotary feed members mounted in said recesses, a driving pinion connected therewith, a driving gear secured to said rotor in position to engage said driving pinion in order to actuate said rotary feed members to feed the explosive charge into the outlet side of said recesses in position to discharge against the buckets of said bucket ring, substantially as described.
8. A rotary internal combustion engine embracing in its construction a rotor element comprising a peripheral bucket ring and a central supporting spider for securing it to a central shaft, a casing provided with a cylindrical head projecting inside said bucket ring, said head being formed with a series of recesses, conduits for conducting the combustible mixture to said recesses, rotor feed members arranged in said recesses to sub-divide them into inlet and outlet chambers and acting to positively feed the combustible mixture into the outlet chambers and to compress it therein, spark plugs located in said outlet chambers to cause ignition of the explosive mixture therein at suitable intervals, said head being also provided with cooling passages for permitting the circulation of liquid between the said recesses, substantially as described.
9. The combination of a rotor element comprising a central spider and a peripheral bucket ring formed by flanges extending laterally on either side of said spider and provided with a series of buckets arranged in said ring, side by side, a casing having opposite cylindrical heads projecting toward each other inside opposite ends of said bucket ring, each head being provided with a series of recesses, rotary feed devices mounted in said recesses to sub-divide them into inlet and outlet chambers, the latter forming explosion chambers, a pair of toothed driving rings detachably secured to said rotor and having operative connection with said rotary feed devices through intermediate pinions, substantially as described.

In witness whereof, I have subscribed the above specification.

SAMUEL L. SAUNDERS.
